Attorney

UNITED STATES PATENT OFFICE.

CHARLES H. TALLEY, OF AURORA, ILLINOIS.

AWNNG-FIXTURE.

1,386,446.

Specification of Letters Patent.

Patented Aug. 2, 1921.

Application filed December 9, 1920. Serial No. 429,461.

To all whom it may concern:

Be it known that I, CHARLES H. TALLEY, a citizen of the United States, residing at Aurora, in the county of Kane and State of Illinois, have invented certain new and useful Improvements in Awning-Fixtures; and I do hereby declare the following to be a full, clear, and exact description of the invention, such as will enable others skilled in the art to which it appertains to make and use the same.

This invention is an improvement on roller awning fixtures, and relates more particularly to the raising and lowering of the awning.

The primary object of this invention is to provide a compact, cheap, safe and better awning fixture, combining simplicity of operation with the minimum amount of applied force.

With this principal object in view my invention consists of a compact application of the law of leverage which is particularly adapted for use in the raising and lowering of awnings with the minimum amount of effort to the operator, and with the simplest possible fixture therefor.

The invention will be more fully understood after reference to the accompanying drawings, in which like parts are indicated by similar reference symbols throughout the several views, and in which:—

Figure 1 is a side view, with parts shown in section, of an improved awning fixture constructed in accordance with the present invention, and shown as applied to a portion of an awning and a building.

Fig. 2 is a front view of the same off center.

Fig. 3 is an enlarged side view of the improved fixture.

Fig. 4 is an interior view of the casting.

Fig. 5 is a vertical sectional view through the wheel.

Fig. 6 is a front elevation thereof.

Fig. 7 is a cross sectional view showing an expanding device for connecting the fixture to the awning shaft.

Fig. 8 is a view in elevation of the cross bar carrying the pinions.

Fig. 9 is a plan view of the cover plate.

Fig. 10 is a plan view of the casting.

Fig. 11 is an edge view of the wheel; and

Fig. 12 is a similar view of the bar 17 and its gear.

Referring more particularly to the drawings, 1 designates generally an awning projecting out from a building wall indicated at 2, and wound about the usual shaft or pole 3. The supporting arm or strut is indicated at 4, and carries a roller 5, movable up and down, in contact with a rod 6 held in brackets 7 and 8, secured to the building wall. A coupling piece 9 is threaded or otherwise formed on one end to receive the adjacent end of the arm or strut 4, and is bifurcated on its opposite end and perforated to receive the pin 10 on which the roller 5 rotates.

The roller 5 is preferably grooved to fit the curvature of the rod 6. A guide piece 11 is also associated with the roller 5 and rod 6 and is substantially U-shaped, being also adapted to engage with the pin 10 of the roller 5 by which it is held in place. The guide piece 11 extends beyond the peripheral edge of the roller and lies about the bar 6, so as to prevent the roller jumping the rod and to direct it in its movement up and down on the same.

The interior construction of the gear box fixture is more particularly disclosed in Figs. 3 to 8 inclusive, in which 12 designates a casting having a wall bracket 13 projecting from one side thereof to receive screws or other fastenings by which the fixture is secured to the building front 2 of Fig. 1. Spider arms indicated at 14 in any suitable number are made to project across one end of the casting 12, or casting end can be closed in order to support a bearing 15. A shaft 16 is received in the bearing 15 and has made in one piece therewith a bar 17 provided with pins 18 and 19 for carrying pinions 20 and 21, respectively. The pinions are adapted to mesh with an internal gear 22 formed within the casting 12. The upper portion of the casting is provided with an overhanging flange 23 at one side thereof, said flange being provided with slots 24 and 25 at diametrically opposite points and substantially in horizontal alinement.

A projecting piece 26 arranged at the upper portion of the flange 23 is provided with an opening 27 to receive a pin 28 projecting from a closure plate 29 which is also preferably of an openwork construction, having a spider 30 providing a central bearing also receiving the shaft 16.

Lugs 31 extend from the edge of the cover 110

plate 29 and are adapted to engage in the notches 24 and 25 of the flange 23. The cover plate is further provided with a lug 32 having a perforation adapted to register 5 with a square opening 33 in an ear 34 on the casting 12.

A headed bolt 35 passes through the openings in the ear 34 and lug 32, and has a square portion adapted to engage the opening 33 and is fastened by a nut. On the bolt 35 is swingingly mounted a pawl 36 having a tooth 37 adapted to engage ribs 38 in a wheel 39, adapted to receive an endless operating rope or chain 40. The pawl 36 10 carries a weighted arm 41 for tending to urge it into engagement with the ribs 38 in order to arrest the progress of the grooved wheel 39. The groove in the wheel 39 is V-shaped and of sufficient size and depth to 15 frictionally receive the rope or chain. The ribs 38 are disposed alternately in order to grip the rope or chain as indicated in Fig. 11.

An eye 42 projects beyond the tooth 37 of 20 the pawl and is arranged to receive the operating cable or chain 40 therethrough in order that an outward or downward pull upon the cable may initially displace the tooth 37 from the rib 38 of the wheel, thus allowing 25 the wheel to be revolved.

The wheel 39 carries a pinion 43 receivable 30 between the pinions 20 and 21, and by which movement is imparted to the awning pole as later described.

35 The awning pole 3 is indicated in Fig. 7 as being hollow, at least at one end, in order to receive the expandible hollow core 44 of an operating gudgeon or trunnion 45. A metal plug 46 internally threaded lies within 40 the expandible portion 44 of the gudgeon and is adapted to be drawn inwardly by the action of a bolt 47.

The shaft 16 is provided with keyways 49 in order to receive the keys 50 on a reduced 45 portion of the gudgeon 45.

A wedge 51 is made on the hilt of the gudgeon to frictionally and tightly bind against the end of the varying sizes of rollers 3.

50 A small pin 52, shown in Figs. 1, 2 and 3 projecting from the casting, is for the purpose of fastening the side of the awning which does not roll up.

Small projections 53 on the lug 32 act as 55 stops to regulate the action of the locking device 36.

In operation the endless rope or chain 40 is pulled downwardly in the desired direction accordingly as the awning is to 60 be raised or lowered. This cord passing through the eye 42 will act to first swing the pawl 36 downwardly in opposition to the action of the arm 41. Further movement of the operating cable will revolve the 65 wheel 39 and with it its pinion 43. The

pinion 43, meshing with the two pinions 20 and 21, will tend to turn the same so that they will step around within the internal gear 22, thus developing in a manner which will be well understood a relatively torque 70 or turning power upon the shaft or pole of the awning. This turning power or torque in the awning pole will result from a small application of force upon the operating cable. 75

It will be obvious that various modifications might be made in the herein described apparatus, and in the construction, combination and arrangement of parts which could be used without departing from the 80 spirit of my invention.

Having thus described my invention what I claim and desire to secure by Letters Patent of the United States is:-

1. A device as described comprising a 85 casting having means to affix it to a support and provided with a bearing and an internal gear, a cover plate adapted to be secured to the casting and having a bearing therein, a grooved wheel mounted inside the 90 cover plate and having a pinion thereon concentric with the internal gear, a shaft journaled in the bearings and passing through said wheel, a bar on said shaft, pinions on the bar meshing both with the first named 95 pinion and with the internal gear, an operating cable passing about the groove in said wheel, a weighted pawl suspended beneath the wheel and adapted to normally check the movement of said wheel, said pawl having sliding engagement with the cable, and means for connecting said shaft to an awning pole, substantially as described. 100

2. A device of the class described comprising a casting having a bracket, an internal gear within the casting, a bearing at one side of the casting, an overhanging flange extending outwardly from said casting and having notches therein, a cover plate provided with a bearing fitted over the front 105 portion of the casting and carrying projections adapted to enter the notches in said overhanging flange, a shaft journaled in said bearings, a bar secured to said shaft, pinions carried by said bar meshing with the 110 internal gear, a grooved wheel also mounted on said shaft, a pinion on the wheel meshing with the first mentioned pinions, a pawl pivoted beneath said wheel and adapted to engage therewith, and a cable extending about the groove in said wheel and loosely fitting through said pawl, substantially as described. 115

3. A device of the character described comprising a housing having a bearing and an internal gear, a flange extending outwardly from the housing and provided with a perforation in the upper portion thereof and with notches at its side portions, a cover plate having a bearing fitted over the front 120 125 130

portion of the housing and provided with a pin adapted to enter the perforation in the flange and with projections for entering said notches, a shaft journaled in said bearings, 5 a bar secured to said shaft, pinions carried by said bar and in mesh with said internal gear, an operating wheel on said shaft, a pinion turning with the operating wheel and meshing with the first mentioned pinions, means to turn the operating wheel from below and to normally hold it motionless, and means for connecting an awning pole to said shaft, substantially as described.

CHARLES H. TALLEY.
